CURTAIN HANGER

Katherine M. Niese, Chicago, Ill.

Application January 6, 1936, Serial No. 57,648

5 Claims. (Cl. 156—21)

This invention relates to improvements in curtain hangers of the type which are adapted to retain the box like plaits, and which are adapted to be readily attached to the curtain or disconnected therefrom to allow the curtain or drapery to be cleaned or laundered.

Heretofore with curtains that were shaped to provide a box like plait, the plait is formed by gathering together or folding portions of the curtain, and the plaits or folds are maintained in shape by stitching or sewing the curtain at any desired distance from the top edge thereof, according to the depth or length of heading it is desired to produce at the upper end of the curtain.

The curtain is then suspended by the usual hooks or devices which are detachably connected to the curtain, some being shaped to provide a hook portion to enter an eye on the curtain ring, and some being shaped to form a loop or ring through which the curtain pole or rod passes.

With such an arrangement and when it is desired to clean or launder the curtain, it is first necessary to remove the pins or hangers, and then rip out the stitching, so that the curtain may be cleaned and will be flat when being ironed or pressed. The box plait is then again formed and stitched to keep the same in place.

This is a very tedious as well as expensive operation, owing to the amount of time of, and care necessary to be exercised by the cleaner or launderer, as such stitching must be removed in order to perform a complete and satisfactory job of cleaning.

It is one of the objects of the present invention to overcome these difficulties, inconveniences and objections, and to provide an improved hanger by means of the use of which the box plait when the same is formed, may be readily held and secured in position by the hanger, and which hanger may be readily detached from the curtain and as readily applied, and when detached the folds of the box plait may be smoothed out or flattened for cleaning purposes.

A further object is to provide in a hanger of this character improved means for maintaining the hanger from shifting or pulling up with respect to the curtain, and which means also serves to hold the gathered portions of the plait in position, all of the parts of the hanger being concealed by the curtain.

To the attainment of these ends and the accomplishment of other new and useful objects as will appear, the invention consists in the features of novelty in substantially the construction,

combination and arrangement of the several parts hereinafter more fully described and claimed and shown in the accompanying drawing illustrating this invention, and in which

Figure 1 is a perspective view of a portion of a curtain or drape having a hanger constructed in accordance with the principles of this invention applied thereto and taken from the front of the curtain.

Figure 2 is a view of a portion of the rear of the curtain shown in Figure 1, on an enlarged scale.

Figure 3 is a detail sectional view of a portion of a curtain showing the box plait therein and with the hanger in section, before the plait is gathered and fastened by the hanger anchoring devices.

Figure 4 is a detail sectional view taken on line 4—4, Figure 2.

Figure 5 is a detail sectional view taken on line 5—5, Figure 4, on an enlarged scale.

Figure 6 is an elevation of a modified form of hanger.

Referring more particularly to the drawing and in the form of the invention shown in Figures 2, 4, and 5, the numeral 10 designates generally the body or shank of the hanger on one end of which is provided a catch 11, which may be formed of a portion of the body or may be formed separately and applied thereto. The numeral 12 designates a pin portion which is connected to the body 10 as at 13 and is bent back upon the body 10, the free extremity of the pin 12 being provided with a point 14 to permit its insertion into the curtain.

The body or shank 10 may be shaped to form a loop or eye 15 of any desired size and configuration and through which eye or loop 15 the curtain pole or rod 16 passes so as to support the curtain to which the hanger is attached and to permit the hangers to slide freely upon the rod or pole. The shank or body 10 may also be shaped to form eyes or loops 17 which are preferably disposed on the inside of the shank or body or opposite to the eye or loop 15, which is preferably disposed on the outside of the body or shank 10. The eye or loop 15 is preferably disposed between the eyes 17.

In use, the curtain 18 is formed into a box or plait 19, the edges 20 thereof overlapping as shown more clearly in Figures 2 and 5, and the pin 12 is passed through the overlapping edges 20 to secure them together as shown in Figures 2, 4, and 5, the point 14 of the pin engaging the catch 11 at the end of the shank or body portion. Obviously, the hanger may be placed in the cur-

tain so that the point 14 of the pin may be uppermost or lowermost as desired. In this position, the eyes or loops 17 will be disposed adjacent the curtain. The box plait 19 will then be secured 5 in position and portions thereof are gathered together as at 21 with the eyes or loops 17 on the shank 10 projecting into the folds. A fastening device, preferably in the form of a pin having a body 22 and a pin portion 23 anchors the hanger 10 to the curtain by passing the pin portion 23 through the folds 21 and also through the eye 17, the body or shank 22 of the pin passing over the shank or body 10 of the hanger. The free end 10 of the pin engages a clasp or catch 24 on the end 15 of the body 22 of the pin. One of these pins or anchoring devices is preferably employed with each of the eyes or loops 17.

With this improved construction it will be manifest that the hanger will not only be secured 20 or anchored to the curtain by the pins or anchoring devices 22, but will also be prevented from shifting or changing its position with respect to the curtain.

In the form of the invention shown in Figure 6, 25 the shank or body portion of the hanger 25 is provided with a catch 26 at one end and the other end is bent back upon itself as at 27, to form a pin 28, the end of which engages the catch 26. The shank or body portion 25 is shaped 30 to form a hook 29 that is adapted to engage in the loop or eye of the curtain ring that usually slides upon the curtain pole, and the shank or body portion 25 on each side of the hook 29 is shaped to form eyes or loops 30 which are on 35 the side of the shank opposite to the side on which the hook 29 is arranged, and through which eyes or loops 30, the pin portion 23 of the anchoring devices 22 are adapted to pass, when this form of the invention is employed, so as to 40 secure the hanger to the curtain and to maintain it against slipping with respect to the curtain.

With either of the forms of the invention it will be manifest that when it is desired to clean 45 or launder the curtain, all that is necessary is to detach the anchor devices 22 and then detach the hanger by withdrawing the pin portion thereof from the overlapping edges of the box plait.

After the curtain has been laundered, the 50 hanger may again be readily applied to the curtain and the box plait gathered and secured in position by the anchoring devices.

This will not only facilitate the cleaning or laundering of the curtain, but will reduce the expense 55 by reason of the fact that the heretofore employed stitching will be dispensed with and it will not necessitate the time of the cleaner to remove or rip out the stitching before the curtain is laundered and then again sew the curtain to 60 form the gathered box plait after the cleaning or laundering operation.

Furthermore, with this improved construction

the pin portion 23 of the anchoring device for the hanger may be so arranged that none of it will be visible from the front of the curtain.

While the preferred forms of the invention have been herein shown and described, it is to be understood that various changes may be made in the details of construction and in the combination and arrangement of the several parts, within the scope of the claims, without departing from the spirit of this invention.

10

What is claimed as new is:—

1. A curtain hanger embodying a body portion, a catch at one end of the body, a pin portion to be inserted through a curtain and adapted to engage said catch, a support engaging portion, 15 and an anchoring loop connected with the body intermediate the ends of the latter, in combination with an anchoring pin adapted to pass through the curtain and through said loop in a direction transverse to the length of said body. 20

2. A curtain hanger embodying a body portion, a catch at one end of the body, a pin portion to be inserted through a curtain and adapted to engage said catch, a support engaging portion connected with and projecting from one side of 25 said body, anchoring loops connected to and projecting from said body on the side opposite to the side on which the said support engaging portion is located, said support engaging portion being disposed between said loops, in combination with an anchoring pin passing through each of said loops and through the curtain in directions transverse to the length of said body portion.

3. A curtain hanger embodying a body portion, 35 a curtain impalement pin, a catch on the body to be engaged by the pin, a support engaging formation on said body, one or more eyes or loops formed on the said body, and means engaging said eyes and the curtain for holding a shaped portion of the curtain in position and for maintaining the hanger against displacement with respect to the curtain.

4. An article of manufacture, a curtain hanger 40 consisting of a unitary structure comprising a shank, a pin connected to the shank, a catch to be engaged by the pin, a support engaging formation on the shank, and one or more eyelets on the shank intermediate the ends of the shank and disposed on the shank opposite to the said support engaging portion.

5. An article of manufacture, a curtain hanger 45 consisting of a unitary structure comprising a shank, a pin connected to the shank, a catch to be engaged by the pin, a support engaging formation on the shank, and one or more eyelets on the shank intermediate the ends of the shank and disposed on the shank opposite to the said support engaging portion, said support engaging portion and said eyes being disposed on opposite sides of said shank.

KATHERINE M. NIESE.
